Inventor,
G. C. Huntress

United States Patent Office.

G. C. HUNTRESS, OF ELKHORN, WISCONSIN.

Letters Patent No. 65,749, dated June 11, 1867.

IMPROVED BUCKLE.

The Schedule referred to in these Letters Patent and making part of the same.

TO ALL WHOM IT MAY CONCERN:

Be it known that I, G. C. HUNTRESS, of Elkhorn, in the county of Walworth, and State of Wisconsin, have invented new and useful improvements in "Trace-Buckles;" and I do hereby declare that the following is a full and exact description thereof, reference being had to the accompanying drawings, making a part of this specification, in which—

Figure 1 represents the side view; and

Figure 2, the top view of the buckle.

The nature of my invention consists in arranging the buckle with two tongues, and thus having a double purchase in connecting the trace with the hamo-strap, when the power is applied.

To enable others skilled in the art to make and use my invention, I will proceed to describe its construction and operation.

I construct the main frame of my buckle of metal, in the form represented by D in fig. 2; and across its under side, at about the middle, I secure a cross-bar, F, by the bent arms E, as shown in fig. 1, the bar F being shown by dotted lines in fig. 2. To the front end of the frame D, on its under side, I attach firmly a projecting pin or lug, A, as shown in fig. 1, this lug being of proper size to fit in the holes made for the tongue B. Within this frame D I pivot a lever, C, by means of a pin, d, the front end of the lever C projecting forward beyond the cross-bar F, and having a tongue or projecting pin, B, secured firmly near its front end, on its under side, as shown in fig. 1. The side-strap H has its end sewed fast to the cross-bar F, and the tug or trace I is then inserted between the same and the frame D, as shown in fig. 1, the tongue B on lever C entering one hole in the trace, and the pin or tongue A, on the front end of frame D, entering another hole, the strain on the buckle being thus thrown partly on the tongue A and partly on the tongue B, and thereby lessening the danger of breaking the tongues, and also the wear on the holes made in the trace.

Having thus described my invention, what I claim, is—

A buckle consisting of the frame D, having the cross-bar F and tongue A formed thereon, and having the lever C, with the tongue B attached, pivoted to the frame, as herein described.

G. C. HUNTRESS.
